UNITED STATES PATENT OFFICE.

JULIUS CHEIN, OF MONTCLAIR, NEW JERSEY.

WAGON.

1,160,574.

Specification of Letters Patent.

Patented Nov. 16, 1915.

Application filed December 9, 1914. Serial No. 876,351.

To all whom it may concern:

Be it known that I, JULIUS CHEIN, a citizen of the United States, and resident of Montclair, in the county of Essex and 5 State of New Jersey, have invented certain new and useful Improvements in Wagons, of which the following is a specification.

My invention relates to improvements in wagons, and the object of my invention is 10 to provide a simple and convenient device of the character described. I accomplish this object by the device illustrated in the accompanying drawings, in which—

Figure 1 is a view of the device complete. Fig. 2 is a detail view of the shaft 15 engaging device.

Similar characters refer to similar parts throughout the several views.

On the underside of a toy wagon body 1 20 I provide a fifth wheel or tongue engaging device comprising a triangular plate 2 of sheet metal having its marginal edge sections 3, 4 and 5 bent over. Adjacent the base of the triangular plate 2 I cut out seats 25 6 and 7 in the bent up edge sections 3 and 4 to receive a flat strip of metal 8 at the end sections 9 of which are carried the axle 10

of the wheels 11. An aperture 12 is provided in the strip 8 and plate 2 to receive a king pin. At the apex of the triangular plate 2 I cut out a seat 2¹, between the projecting end sections or ears 3¹ and 4¹ of the edge sections 3 and 4 respectively, to receive a tongue of the wagon.

I claim—

1. A wagon provided on its under side with a triangular plate having a bent over edge section forming ears at the apex thereof and having cut out seats adjacent its base receiving a bar which engages the axle 35 substantially as shown and described.

2. A wagon provided on its under side with a plate having a bent over edge section forming ears at the apex thereof and an axle strip extending from its base section 40 substantially as shown and described.

Signed at New York, in the county of New York and State of New York, this 1st day of December, A. D. 1914.

JULIUS CHEIN.
